UNITED STATES PATENT OFFICE.

LYMAN E. BURDICK, OF BERLIN, NEW YORK.

SHIRT-BUTTON-LOCATING ATTACHMENT.

1,160,492.

Specification of Letters Patent. Patented Nov. 16, 1915.

Application filed December 26, 1912. Serial No. 738,544.

To all whom it may concern:

Be it known that I, LYMAN E. BURDICK, a citizen of the United States, residing at Berlin, county of Rensselaer, and State of New York, have invented certain new and useful Improvements in Shirt-Button-Locating Attachments, of which the following is a specification.

The invention relates to such improvements and consists of the novel construction and combination of parts hereinafter described and subsequently claimed.

Reference may be had to the accompanying drawings and the reference characters marked thereon, which form a part of this specification.

Similar characters refer to similar parts in the several figures therein.

Figure 1 of the drawings is a plan view 20 of a broken-away portion of a sewing-machine table, and sewing-machine showing my improved shirt-button-locating attachment applied thereto. Fig. 2 is a view in front elevation of the same. Fig. 3 is a view 25 in perspective of the attachment removed from the table. Fig. 4 is a vertical cross-section of the attachment taken on the broken line 4-4 in Fig. 3. Fig. 5 is a vertical cross-section of the attachment taken 30 on the broken line 5-5 in Fig. 3.

The principal object of the invention is to facilitate attaching, by means of a sewing-machine, buttons to one flap of a shirt-bosom in position to register accurately with buttonholes previously formed in the other bosom-flap.

Referring to the drawings wherein the invention is shown in preferred form, 1, is a sewing-machine table upon which is mounted a button-sewing machine having a bed-plate, 2, a button-chuck, 3, and a needle, 4.

I have shown only the front portion of the machine, which may be of any known type adapted for the purpose.

My attachment comprises in part a plate, 5, attached to the table by means of standards, 6, in position to overlie the extreme front end of the bed-plate 2.

Upon the plate, 5, is mounted a slide-plate, 7, provided with a longitudinal slot, 8, adapted to receive the shanks of a pair of posts, 9, which project upward from the plate, 5, and form guides for the plate, 7, in its longitudinal sliding movement.

The plate, 7, is shown as a built-up construction having at one end an L-shaped ex-

tension, 10, and at the other end an L-shaped extension, 11, both extending rearwardly from the body of the plate.

The extension, 10, has a stud, 12, projecting upwardly therefrom adapted to enter buttonholes in the respective front ends of the neckband of a shirt, and the end-extension, 11, is formed with a slideway, 13, in which is movably mounted a slide, 14, having upwardly projecting spurs, 15, upon which the body-portion or skirt of a shirt can be impaled. A coil-spring, 16, tends to draw the slide, 14, away from the stud 12.

The attachment is mounted upon the sewing-machine table with the plates, 5 and 7, parallel with the front edge of the table and just in front of the button-chuck, 3, and with the stud, 12, and slide, 14, substantially in line with the needle, 4, on opposite sides 70 thereof.

At about the middle of the plate, 5, I have shown fixed thereupon a pair of rearwardly extending arms, 17 and 18, upon one of which, 17, is adjustably mounted a gage, 19, 80 cut away at, 20, to receive the button-chuck, 3; the adjustment of the gage being accomplished by means of a screw, 21, inserted through a slot in the shank of the gage into the arm 17. The work-engaging surfaces on 85 the gage, 19, are located in rear of the needle a distance corresponding with the desired distance from the edge of the bosom-flap to the center of the several buttons.

The plate, 7, has an upturned end, 22, 90 forming a handle whereby the plate can be slid along the posts 9.

The manner in which the device is used is as follows: The buttonholes in the neckband and front of the shirt having been formed, the buttonholed flap, 23, of the bosom is inverted upon the bosom-flap, 24, to which the buttons are to be attached; and in this position, the two bosom-flaps are placed upon the plate, 7, and the stud, 12, is inserted through the buttonholes in the respective front ends of the neckband 25. The under member of the shirt-front, which is the one to which the buttons are to be attached, is then stretched by hand and impaled upon the pins, 15, with the edge of its bosom-portion against the gage 19. The upper buttonholed member of the shirt-front is then drawn into line with the under member; and the plate, 7, and the shirt are together slid along the plate, 5, until one of the buttonholes in the upper bosom-mem- 95 100 105 110

ber is brought directly beneath the needle, 4, in which position the plate, 7, is held while the upper buttonholed bosom-member is drawn back as indicated by dotted lines 5 in Fig. 1, and the button is stitched to the under bosom-member in the usual manner by means of the sewing-machine. After a button has been thus attached, the upper member of the shirt is again drawn into line 10 with the under member; and the shirt and the plate, 7, are again adjusted to bring another buttonhole directly under the needle in which position the plate is held while the upper bosom-member is drawn out of the way and the button is stitched to the under member. In this manner the positions of the several buttons can be accurately located so that they will register properly with the respective buttonholes, and the labor and inaccuracy of marking the positions of the buttonholes upon the shirt bosom are avoided.

The arms, 17 and 18, are preferably located below the level of the plate, 5, being 25 adapted to embrace between them the bed of the machine upon which the body of the plate, 5, rests.

The standards, 6, are shown capable of vertical adjustment, whereby the attachment 30 can be applied to machines at different heights from the table.

While my attachment is particularly adapted for locating the buttons on shirts, it is adapted for locating in a similar manner 35 the buttons on other garments in proper relation to the respective buttonholes which they are to engage.

For certain purposes of the invention the plate, 7, may be slidably mounted in any 40 known manner in proper relationship to the sewing-machine.

What I claim as new and desire to secure by Letters Patent is—

1. A button-locating attachment for button-sewing machines comprising a slide-plate which supports the fabric upon its upper face having at one end an upwardly projecting buttonhole-engaging member and

at its other end a fabric-engaging member and provided with means whereby it is 50 adapted to be mounted in longitudinal relation to a button-sewing machine.

2. A button-locating attachment for button-sewing machines comprising a slide-plate which supports the fabric upon its upper face having at one end an upwardly projecting stud and at the other end an upwardly projecting spur, and means whereby said slide-plate is adapted to be mounted in longitudinally slidable relation to a sewing- 55 machine with said stud and said spur on opposite sides of the sewing-machine needle. 60

3. A button-locating attachment for button-sewing machines comprising a slide-plate which supports the fabric upon its upper face having at one end an upwardly projecting buttonhole-engaging member, a member yieldingly mounted at the other end of said slide-plate, an upwardly projecting spur carried by said yieldingly mounted 65 member, and means whereby said slide-plate is adapted to be mounted in longitudinally slidable relation to a sewing-machine with said spur and said buttonhole-engaging member on opposite sides of the sewing- 70 machine needle. 75

4. A button-locating attachment for button-sewing machines comprising a supporting-plate, a fabric-gage mounted upon said plate, a slide-plate which supports the fabric upon its upper face having at one end an upwardly projecting buttonhole-engaging member and at its other end a fabric-engaging member, said slide-plate being mounted upon said supporting-plate with 80 capability for longitudinal slide movement, and means for mounting said supporting-plate in fixed relation to a button-sewing machine. 85

In testimony whereof, I have hereunto set 90 my hand this 23rd day of December, 1912.

LYMAN E. BURDICK.
